UNITED STATES PATENT OFFICE.

ERNEST ENGHOLM, OF NEW YORK, N. Y.

TOBACCO-PIPE.

No. 873,222.

Specification of Letters Patent.

Patented Dec. 10, 1907.

Application filed April 29, 1907. Serial No. 370,927.

To all whom it may concern:

Be it known that I, ERNEST ENGHOLM, a citizen of the United States, residing at New York city, Bronx, county and State of New York, have invented new and useful Improvements in Tobacco-Pipes, of which the following is a specification.

This invention relates to a tobacco pipe in which the nicotin and saliva are entrapped 10 by a vessel removably fitted within the pipe-stem, so that by removing a filled vessel and replacing it by a new one, cleanliness is insured.

In the accompanying drawing: Figure 1 is 15 a longitudinal section of my improved tobacco pipe; Fig. 2 a side view of the same, showing the parts separated, and with the mouth-piece partly broken away; Fig. 3 a cross section on line 3—3, Fig. 1; Fig. 4 an 20 enlarged longitudinal section through the trap, and Fig. 5 an end view thereof.

Into the neck 10 of the bowl 11 is screwed a plug 12, to which is removably secured by means of a slip-joint, one end of the cylindrical pipe-stem 13. The other end of this stem is removably attached to the mouth-piece 14 by means of a threaded nipple 15. Within stem 13 is removably fitted a trap 25 consisting of a cylindrical barrel or vessel 16, the heads 17 of which have central perforations 18. The forward perforation serves for the admission of a tube 19 that extends from bowl 11 through plug 12 into the barrel, and opens within the latter. The rear perforation 30 serves for the admission of a tube 20 that extends from the mouth-piece 14 into the barrel and also opens within the same. The two inner ends of tubes 19, 20, inclosed by the barrel are deflected in opposite directions, to prevent a direct passage of smoke 35 or liquid through the same. Each head 17 is grooved for the accommodation of a packing ring 21 that insures a tight joint between the head and the tube extending through 40 said head. Within the barrel may be contained a cylindrical lining 22, made of absorbent material and having centrally perfo-

rated ends 23, for accommodating the tubes 19, 20, respectively.

It will be seen that by the construction described, the interior of the barrel is entirely separated from the interior of stem 13, the perforated heads 17 serving not only to close the ends of the barrel, but also to constitute bearings for the inner ends of tubes 19, 20. 50

In use the nicotin from bowl 11 will flow through tube 19 into the barrel, and the saliva from mouth-piece 14 will also flow into the barrel through tube 20. In this way the nicotin is prevented from reaching the 60 mouth, and the saliva is prevented from reaching the bowl, so that cleanliness is insured. As soon as the barrel has been sufficiently filled with an accumulation of saliva and nicotin, it is removed and thrown away, 65 while a fresh barrel is inserted. Thus cleaning of the pipe proper is avoided and a pleasant smoke is insured.

I claim:

1. A tobacco pipe provided with a bowl, a 70 mouth-piece, a stem, a vessel inclosed within the stem and having a pair of centrally perforated heads, and a pair of tubes entering said heads and communicating with the bowl and mouth-piece respectively, the inner ends 75 of said tubes being deflected within the vessel in opposite directions, substantially as specified.

2. A tobacco pipe provided with a bowl, a 80 mouth-piece, a stem, a vessel inclosed within the stem and having a pair of centrally perforated heads, a pair of tubes entering said heads and communicating with the bowl and mouth-piece respectively, the inner ends of said tubes being deflected within the vessel 85 in opposite directions, and an absorbent lining inclosed by the vessel, substantially as specified.

Signed by me at New York city, (Manhattan,) N. Y., this 27th day of April, 1907.

ERNEST ENGHOLM.
